Writing PRINTING type

PC 3644

Rec'd

United States Patent Office.

A N D R E W L I T T L E, O F N E W Y O R K, N. Y.

Design No. 3,644, dated August 31, 1869.

DESIGN FOR PRINTING-TYPE.

The Schedule referred to in these Letters Patent and making part of the same.

To all whom it may concern:

Be it known that I, ANDREW LITTLE, of the city, county, and State of New York, have originated and designed a new Design for Printing-Type; and that the following is a full, clear, and correct description thereof, reference being had to the accompanying drawings, making a part of this specification, in which several letters of a fount of type are shown, made in accordance with my design, which design is preserved in all symbols, signs, or other characters used.

What is claimed as new, is—

The within design for a printing-type, as shown.

ANDREW LITTLE.

Witnesses:

A. SIDNEY DOANE,
H. W. HENLEY.
